UNITED STATES PATENT OFFICE.

JAMES E. STEPHENSON, OF ROCHESTER, NEW YORK, ASSIGNOR TO GENERAL RAILWAY SIGNAL COMPANY, OF GATES, NEW YORK, A CORPORATION OF NEW YORK.

PIPE CARRIER.

Application filed January 5, 1923. Serial No. 610,807.

This invention relates to anti-friction pipe carriers for remote mechanically controlled traffic controlling devices for railroads.

Various methods have been employed for mechanically operating switches, signals, or other traffic controlling devices located a considerable distance from a central point or tower. From these various methods has survived the well-known reciprocatory pipe line construction, which is extensively used for this purpose in this country. This method of remote control is carried out by providing an operating rod between the tower and the traffic controlling device, which is arranged so that it may be moved back and forth in one direction or the other by the switch or signal lever in the tower and in turn cause a corresponding movement of the switch or signal. It is, therefore, important that such a pipe line construction should be supported so as to have a minimum of friction.

In practice, two particular types of anti-friction pipe carriers have come into general use and are recognized as standards. Although these two types of pipe carriers are very similar, there is sufficient difference so that certain parts of one type cannot be used exchangeably with similar parts of the other. If two or more operating pipes extend along the trackway near to each other, it is desirable and economical to space them very closely to each other, thereby allowing the supporting frame or pedestal of one pipe carrier to serve a similar function in making up a pipe carrier support for the adjacent pipe line. It is thus seen that it is economical both as to the number of parts needed and as to the amount of space used when a plurality of pipe lines are grouped together, as just explained. However, if the two different types of pipe carriers which have become standard are used in the same interlocking plant, it is found difficult to install them in the economic manner just referred to, because the support or pedestal of either of these types is not adapted for cooperation with the remaining parts of the other kind.

With the above and other considerations in mind, the present invention contemplates the provision of means used in connection with a pedestal of one type of pipe carrier so that it may be used as a cooperating

pedestal of the other type. More specifically, the present invention consists of the provision of a combined roller journal and pedestal bracing and connecting pin, which has one end constructed to fit one of the standardized pipe carrier pedestals, and has the other end constructed to fit the other type.

Other objects, purposes and characteristic features of the invention will appear as the description thereof progresses.

In describing the invention in detail, reference will be made to the accompanying drawings, in which:—

Figure 1 shows a side elevation of a pair of pipe carriers commercially known as the universal type and arranged in the usual way, whereby one pedestal forms a common support for the rollers of two pipe carrier units;

Fig. 2 is an end elevation of the devices shown in Fig. 1;

Fig. 3 is a view similar to Fig. 1 of another type of pipe carrier, which is known commercially as the E. Z. type, and which will for convenience be designated as such hereinafter;

Fig. 4 is an end elevation of the devices shown in Fig. 3;

Fig. 5 shows a series of three pipe carrier units, the lefthand one of which is of the universal type, the righthand one of the E. Z. type, and the middle one of the combined universal and E. Z. type;

Fig. 6 is a plan view of the devices shown in Fig. 5; and

Fig. 7 is a perspective view of the combined journal and adapter pin forming the new element of the novel combination embodying the present invention.

In Figs. 1 and 2 have been illustrated a pair of pipe carrier units, comprising three pedestals or supporting frames F of the general shape shown and having legs 1 terminating in perforated feet fastened to a suitable support, such as the tie 2 shown, by lag bolts 3. These frames or pedestals F are provided with a horizontally extending slot which is slightly tapered from each outside toward the middle to form a runway for the bearing pins 4 of the lower rollers 5. It is thus noted that upon longitudinal movement of a pipe, it is adapted to rest on the roller 5 and is supported in a sub-

stantially frictionless manner because the bearing pins 4 may roll in the horizontal slots of the pedestals F with very little, if any, rubbing engagement of parts.

5 The top portion of the pedestals F is bifurcated to form extensions 6 and 7, the bifurcation being rounded to form a bearing portion. Retaining rollers 8 having bearing pins 9 integral therewith are supported in 10 the bearing portion between the extensions 6 and 7. In order to keep these retaining or top rollers 8 in position, suitable retaining and bracing plates 10 are provided. These bracing plates 10 are perforated and 15 are held in place by cotter pins 11 so that the downwardly extending end portions thereof are spaced a short distance from the bearing pins 9 to maintain the rollers 8 in their operative position, and also serve 20 to maintain a definite and predetermined spacing between the pedestals or frames F.

In Figs. 3 and 4 have been illustrated another well-known type of pipe carrier commercially known as the E. Z. type. The 25 pedestals F of this type of pipe carrier are very similar to the universal type shown in Fig. 1. It should, however, be noted that the extensions 6' and 7' of the top bifurcation are spaced further apart and are not 30 quite as long. The lower roller of the E. Z. type carrier is substantially the same as that of the universal type, and therefore has been designated with the same reference character. The top roller, however, is considerably different, and consists of a stationary bearing pin 12 upon which is rotatably supported the roller 13. As more specifically shown in Fig. 6, this bearing pin 12 has a semi-circular portion of each end thereof 40 cut away to provide room for the overlapping end of an adjacent bearing pin. Also, a groove has been provided transverse to the axis of the bearing pin 12 near each end thereof, to allow the lug 14 extending from 45 the side of the extensions 6' and 7' respectively to engage the bearing pin and prevent both endwise and rotary movement thereof. The extensions 6' and 7' are perforated to receive a cotter pin 15 extending 50 directly over the overlapped portions of the roller pin 12, thereby holding the ends of both of the adjacent roller pins in operative position.

55 In order to build up a series of pipe carrier units, some pedestals of which are of the universal type and others are of the E. Z. type, a special adapter A has been provided which serves as a journal for the top roller and also as a reenforcing means between two pedestals, one of which is of the universal and the other of the E. Z. type. This adapter A consists of a body portion having a diameter to receive the roller 13. One end of this adapter A is constructed 65 substantially the same as the bearing pins

12 of the E. Z. construction. The other end, however, terminates in an upstanding arm 16 corresponding in thickness to the retaining and bearing plate 10 shown in the universal type pipe carrier and provided 70 with a hole at the proper point, so that if the cotter pin 11 is put in place, the adapter A will be properly disposed with respect to the pedestals F.

This adapter A has been illustrated in its 75 operative position in connection with the middle units of the three pipe carrier units illustrated in Figs. 5 and 6, and shows how a series of pipe carrier units may be built up out of material of two distinctive types 80 in a manner so that the several elements properly cooperate, whereby economy in space and material may be obtained.

The adapter comprising the novel element 85 of the present invention is found to be very valuable in many instances. For instance, it is often found that remote control mechanical pipe lines for operating traffic controlling devices have already been installed, that it is desired to provide an operating connection to another traffic controlling device located in the same direction along the track, and that pipe carriers of another type are at hand and are to be installed as 90 a continuation of these series of pipe carrier units already in place. Obviously, the use of the adapter A is a simple and inexpensive solution to a problem of this kind. The same advantages are experienced in 95 using this novel type of adapter in connection with the replacement of broken pedestals and other parts of pipe carriers of either type in use.

100 Having thus shown and described only one specific type of adapter, and the manner in which it may be applied in practice, it should be understood that various modifications, changes and adaptations may be made without departing from the spirit and scope 105 of the present invention or its mode of operation.

110 What is desired to be secured by Letters Patent of the United States, is:—

1. An adapter pin for connecting pipe carrier pedestals of different types described 115 and for pivotally supporting a roller comprising, a cylindrical body portion having one end thereof partly cut away to form a semi-circular extension, and means having a perforation extending transversely from the other end of said body portion.

120 2. An adapter pin for connecting pipe carrier pedestals of two different types used 125 for supporting the pipes for operating traffic controlling devices for railways comprising, a cylindrical body portion having a transverse groove near one end thereof to resist rotation and to form an interlocking engagement with a pedestal of one type, and means extending from one side of the center 130

line of the other end of said body portion having a hole therein and adapted to be fastened to a pedestal of another type.

3. An adapter pin for connecting pipe carrier pedestals of two different types used for supporting pipes for operating railway traffic controlling devices comprising, a cylindrical body portion having means at

one end thereof to form an interlocking engagement with a pedestal of one type, and differently formed means at the other end thereof to form an interlocking engagement with a pedestal of a different type.

In testimony whereof I hereby affix my signature.

JAMES E. STEPHENSON.
